UNITED STATES PATENT OFFICE.

HENRY DRIEHAUS, OF HENDRICKS, PENNSYLVANIA.

TOOL-HOLDER.

SPECIFICATION forming part of Letters Patent No. 723,848, dated March 31, 1903.

Application filed August 26, 1902. Serial No. 121,137. (No model.)

To all whom it may concern:

Be it known that I, HENRY DRIEHAUS, a citizen of the United States, residing at Hendricks, in the county of Montgomery and State 5 of Pennsylvania, have invented certain new and useful Improvements in Tool-Holders; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 The object of my invention is to provide an implement which combines several tools into one.

20 A further object of my invention is to provide a novel means of utilizing the handle of the pliers to form reamers, screw-setters, nail-punches, &c.

25 With these objects in view my invention consists in the arrangement and construction of my pliers and handle.

30 My invention also consists in certain other novel features of construction and in combination of parts, which will be first fully described and afterward specifically pointed out in the appended claims.

35 Referring to the accompanying drawings, Figure 1 is a side elevation of my invention. Fig. 2 is an elevation of the end of one of the handles. Fig. 3 is an edge view of the top of the pliers. Fig. 4 is a detail view of the locking-piece. Fig. 5 is a top plan of the pliers. Fig. 6 is a horizontal section of the lower end of leg 4.

40 Like numerals of reference indicate the same parts throughout the several figures, in which—

1 indicates the pliers formed of the jaws 2 and 3, having handles 4 and 5. Said jaws are pivoted at 6.

45 7 indicates wire-cutters on each side of the pivot 6.

A hammer-head 8 is formed on the jaw 2, and a riveting-point 9 is formed on the jaw 3. The inner side of the jaw 3 is grooved or serrated, forming a wrench 10.

50 The jaws 2 and 3 meet at their ends, forming cutting-pliers 11. The jaw 2, however, is provided with a raised portion 12, which

extends beyond the cutting edge of jaw 2 and into the jaw 3. Said extension forms a wall 13 and tapers to the points 14 and 15, between which is formed a notch 16. The jaw 3 is also raised at 17 and is cut away to conform to the jaw 2.

On the handle 5 I form a screw-driver 18, and the lower portion of the handle 4 is hollow and provided with a slot 19 on the inner side of said handle. A tool 20 is provided with a locking-piece 21, securely fastened to said tool by means of the pin 22. Said locking-piece 21 is provided with a cam-shank 23, through which the pin 22 passes, and is also provided with a lug 24.

Having thus described the several parts of my invention, its operation is as follows: It is frequently desired to draw nails with pliers, and it is always extremely difficult to get the edges of the pliers under the head of a nail driven in the wood. The flat surface of the ordinary pliers makes it difficult to get them below the surface of the wood in order to get under the head of a nail. I have therefore constructed my pliers with raised portions, one of said portions extending beyond the cutting edges of the pliers and tapering to points, so that this projection will straddle the nail. By reason of the raised position of this portion it can be readily buried in the wood, and by reason of the extended position of the portion it can straddle the nail before the cutting edge of the jaw comes in contact with the wood. This projecting feature of the raised portion is very material for the foregoing reason. It furthermore forms a side wall for the cutting-pliers, thereby absolutely preventing an object from slipping past said wall while being gripped by the cutting-pliers.

The handle 4, as before described, is designed to carry a removable or detachable tool. Said tool is inserted in the handle while the locking-piece is in the position shown in dotted lines in Fig. 3, as the cam-shank 23 will pass into the slot 19 only while in this position. When the tool has been inserted to the desired point, the locking-piece is turned parallel with the handle, the lug 24 springing down into the slot 19, while the cam-shank 23 firmly engages the sides of the slot 19, thereby securely locking the tool in position.

It is my intention to provide a number of tools to be inserted as described, as reamers, screw - setters, nail - punches, gimlets, &c., each to be provided with a locking-piece 21.

5 Having thus fully described my invention, I do not wish to be understood as limiting myself to the exact construction herein set forth, as various slight changes may be made in form and construction, and I consider myself clearly entitled to all such changes and modifications that fall within the limit and scope of my invention as defined by the following claims.

I claim—

15 1. A tool having one of its handles formed hollow and provided with a slot, an implement adapted to be inserted in said hollow

handle, and a cam locking-piece carried on said implement to lock the same with said handle.

2. A tool having one of its handles formed hollow, an implement adapted to be inserted in said hollow handle, a cam locking-piece adapted to lock said tool to said handle and means on said cam locking-piece of engaging 25 said handle to hold said locking-piece in a locked position.

In testimony whereof I affix my signature in presence of two witnesses.

HENRY DRIEHAUS.
